UNITED STATES PATENT OFFICE

2,484,414

MUSICAL EATING BOWL

Jeanne Picard Mahan, Pittsburgh, Pa.

Application January 16, 1948, Serial No. 2,790

10 Claims. (Cl. 84—95)

1

This invention relates to new and useful improvements in eating bowls and the primary object of the present invention is to provide an eating bowl that is so designed as to sound a musical alarm as the food in the bowl is consumed to a predetermined point, thus delighting and amusing the person, and helpfully aiding and encouraging the training of the person to eat from the bowl.

Another object of the present invention is to provide a musical eating bowl including a music box and novel and improved means for actuating the music box as food in the bowl is consumed.

Another object of the present invention is to provide a musical eating bowl including a removable sound device, for complete and sanitary cleaning of said bowl and furthermore for convenient heating or serving of the food prior to actual use and/or consumption in connection with the sound device.

Another important object of the present invention is to provide a musical eating bowl including a music box, means for actuating the music box as food is removed from the bowl, and embodying novel and improved means for adjusting the actuating means so that the same will be responsive to a predetermined quantity of food removed from the bowl.

A further object of the present invention is to provide a musical eating bowl, the parts of which are quickly and readily assembled or disassembled, facilitating the convenient inspection of parts, the cleaning or replacement of parts, or the storage or shipment of the same.

A still further aim of the present invention is to provide a musical eating bowl that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the present invention, and showing the eating dish removed therefrom;

Figure 2 is a vertical sectional view taken substantially on the plane of section line 2—2 of Figure 1, and showing the eating dish in section applied thereto;

Figure 3 is a sectional view taken substantially

on the plane of broken section line 3—3 of Figure 1;

Figure 4 is a perspective view of the musical box braking arm actuating means used in conjunction with the present invention;

Figure 5 is a perspective view of the present invention in assembled form; and

Figure 6 is a perspective view of the pivotal and rockable connecting means used in conjunction with the present invention.

Referring now to the drawings in detail, wherein for the purpose of illustration, there is disclosed a preferred embodiment of the present invention, the numeral 10 represents a sleeve-like body or casing open at both its upper end 12 and its lower end 14.

Fixedly secured to the inner periphery of the body 10, adjacent the lower end thereof, is a plurality of circumferentially spaced support strips 16, the upper edges of which are coplanar and are spaced parallel to the lower end 14 and upper end 12 of the body 10, to frictionally support a preferably annular supporting plate or base plate 18. Struck upwardly from the supporting plate 18, is a substantially rectangular guide plate 20 having a central opening 22 therein for a purpose that will later be more fully described. Also, preferably struck upwardly from the supporting plate 18, is a bearing or stop plate 24, the upper edge 26 of which is spaced relative to the braking arm 28 of a conventional, preferably rectangular music box 20, preferably of the wind type, that is suitably fixed on the inner or upper face of the supporting plate 18.

The numeral 32 represents generally, the lever member used in conjunction with the present invention for actuating the braking arm 28. This lever member 32 comprises a substantially channel-shaped element 34, the web portion 36 of which is integrally formed with an elongated outer lever or arm 38 having a downwardly flared reduced end 40, and a threaded portion 42 adjacent the end 40. Integrally formed with and projecting outwardly from the web portion 36, in an opposite direction from arm 38, is a contact lever or arm 43, the longitudinal axis of which is preferably spaced parallel to the longitudinal axis of arm 38, so that one corner of the music box 30 may be positioned relatively close to the arm 43 and channel-shaped element 34, with the free end of the contact arm 43 disposed beneath the braking arm 28 and normally, frictionally engaging the upper edge 26 of the stop plate 24.

Depending from the central portion of a preferably annular pressure plate or movable supporting

plate 44 having excess openings 46, is a pair of spaced parallel attaching ears 48 that are connected by one leg 50 of a substantially U-shaped link 52. The opposite leg 54 of the link 52 frictionally engages suitable apertures provided in the upper ends of a further pair of spaced parallel attaching ears 56 that are fixed to and extend upwardly from the support plate 18, so that the pressure plate may pivot or slide upwardly and downwardly relative to the support plate 18.

Extending transversely through opposed apertures 58 provided in the leg portion of the channel-shaped element 34, is a pivot pin 60 that is pivotally connected to the depending attaching ears 48. A further pivot pin 62 extends transversely between a further pair of opposed apertures 64 provided in the leg portions of the channel-shaped element 34 and its ends are pivotally secured to the fixed upstanding ears 56 carried by the support plate 18.

Frictionally positioned on the upper face of the pressure plate 44, is a suitable eating dish 66 having an annular flanged portion 68 that is adapted to frictionally engage the upper end 12 of the body 10, to limit the downward movement of the dish 66 relative to the body 10.

It should be noted, that there is adjustably mounted on the portion 42 of arm 38, a counter-balancing nut 68 for a purpose which will later be more fully apparent.

In practical use of the present invention, food is placed in the dish 66, so that the combined weight of the dish and the food therein will cause the pressure plate 44 to be extended downwardly, thus pivoting the arm 38 upwardly and the arm 43 will frictionally engage the upper edge 26 of the support plate 24. In this position, the braking arm 28 for the music box 30 will be extended downwardly in its normal position and sound will not be emitted from the music box.

As a certain amount of the food is removed from the dish 66, the counter-weight 68 will overbalance the weight of the dish 66 and the remaining food in the dish 66, so that the arm 38 will pivot downwardly in the guide opening 22, and the arm 43 will pivot upwardly to frictionally engage the braking arm 28, to force the same upwardly thus actuating the music box 30 and a musical sound will be emitted therefrom.

Obviously, by adjusting the counter-weight 68, the device may be regulated for actuation by varying amounts or quantity of food that is removed from the dish, so that as an infant becomes larger it will be necessary for more food to be removed from the dish before the music box is actuated.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A musical eating bowl comprising a hollow-body open at its upper end, a pressure plate mounted for upward and downward movement in said body, a music box mounted in said body including an outwardly extending braking arm

normally in a lowered position, means for actuating the braking arm to a raised position for activating the music box, means operatively connecting said actuating means to said pressure plate, and means for normally holding the pressure plate in a lowered position and said actuating means disengaged with the braking arm.

2. The combination of claim 1 wherein said actuating means includes a pivotal lever.

3. A musical eating bowl comprising a hollow-body open at its upper end, a pressure plate mounted for upward and downward movement in said body, a music box mounted in said body including an outwardly extending braking arm normally in a lowered position, an elongated pivotal lever for actuating the braking arm to a raised position for activating the music box, means for guiding and limiting the pivotal movement of said lever, means received on the lever for adjusting the center of gravity of said lever, means operatively connecting said actuating means to said pressure plate, and means for normally holding the pressure plate in a lowered position and said lever disengaged with the braking arm.

4. The combination of claim 3 wherein said means for adjusting the center of gravity of said lever includes an adjustable counter-balancing member carried by said lever.

5. The combination of claim 3 wherein said means for normally holding the pressure plate in a lower position includes a dish filled with edibles, said lever over-balancing said pressure plate and the dish supported on said pressure plate upon removal of predetermined quantity of edibles from the dish.

6. The combination of claim 3 wherein said means operatively connecting said actuating means to said pressure plate includes a pair of bearing plates fixed to and depending from said pressure plate, a further pair of fixed bearing plates mounted in said body, and means pivotally securing said lever to said first-mentioned pair of bearing plates and pivotally and rockably securing said lever to said further pair of bearing plates.

7. The combination of claim 6 wherein said means includes a removable U-shaped member.

8. Means for actuating the braking arm of a music box comprising a housing adapted to receive a music box, a rockable lever mounted in said housing and including a pair of end portions, one end portion of said lever adapted to engage the braking arm of a music box, a counter-weight adjustable on the remaining end portion of said lever and normally urging the other end of said lever upwardly against the braking arm of a music box, and a pressure member acting on said lever and retaining the same out of engagement with the braking arm of a music box.

9. The combination of claim 8 wherein said rockable lever includes a threaded portion receivably engaging the counterweight.

10. Means for actuating the braking arm of a music box comprising a housing adapted to receive a music box, a rockable lever mounted in said housing and including a pair of end portions, one end portion of said lever adapted to engage the braking arm of a music box, a counter-weight adjustable on the remaining end portion of said lever and normally urging the other end of said lever upwardly against the braking arm of a music box, a pressure plate, a pair of ears depending from said pressure plate, a U-shaped

pivot link having one leg engaged with said ears, a further pair of ears mounted in said housing and engaging the free leg of said pivot link, and means securing said first-mentioned ears to said lever.
